CLAIM

The ornamental design for a paddle for holding a flight of cone shaped smoking articles, as shown and described.

DESCRIPTION

FIG. 1 is a top plan view of a paddle for holding a flight of cone shaped smoking articles showing my new design.

FIG. 2 is a left side elevational view thereof and a right side being a mirror image;

FIG. 3 is a bottom view thereof;

FIG. 4 is a left side view thereof; the right being a mirror image; and,

FIG. 5 is a perspective view thereof showing the paddle for holding a flight of cone shaped smoking articles in a state of use with cone shaped smoking articles.

The broken lines in the drawings depict portions of the paddle for holding a flight of cone shaped smoking articles that form no part of the claimed design. The additional broken lines in FIG. 5 illustrating two cone shaped smoking articles depicts environmental subject matter only and forms no part of the claimed design.
